PAPER TOWEL HOLDER

Carmin A. Castellano, Clarks Summit, Pa., assignor to
Consolidated Molded Products Corporation, Scranton,
Pa., a corporation of Delaware
Filed May 16, 1963, Ser. No. 280,844
4 Claims. (Cl. 242—55.2)

This invention relates to holders for dispensing rolled articles and, in particular, to an improved form of holder for dispensing rolled paper towels and the like.

In accordance with the present invention a simple, inexpensive roll holder is provided which includes a back bar and roll-supporting arms connected to the back bar by means of an easily assembled hinge joint enabling the arms to be folded against the back bar and unfolded to an erected position to receive between them, and resiliently engage, the ends of a roll of towels or the like.

More particularly, the back bar has a slot in each of its two longitudinal extremities for slidably and rockably receiving a downwardly and laterally projecting tongue or tongues formed on the inner face of each end bar. One or more detents, formed on the extremity of the laterally projecting portion of each of the tongues, to make the tongues of slightly greater extent in one dimension than the accommodating slot, retains each tongue in the slot with capacity for sliding movement to enable the end bars to be moved to a folded position longitudinally overlying the back bar and unfolded to an erect position, generally perpendicular to the respective longitudinal extremities of the back bar. A flange on each of the end bars engages an individually mating shoulder on the back bar when the corresponding end bar is in the erect position. The flanges and shoulders thereby act as stops limiting the rocking movement of the end bars.

The elements of the roll holder can be formed of plastic by means of injection molding. Inasmuch as the end bars are essentially identical, only two molds are required for producing all of the elements of the roll holder. By virtue of the novel hinge joint provided between the end bars and the back bar, the roll holder can be assembled easily without tools and the end bars can be folded and unfolded without danger of detachment from the back bar. Moreover, the arrangement of the arms and hinge joints are such that they can be sprung to enable a roll to be inserted between them and will resiliently engage and retain the roll during use.

For a better understanding of the present invention, reference may be had to the accompanying drawings in which:

FIGURE 1 is a front view in broken section of roll holder embodying the invention, with the end bars folded;

FIGURE 2 is a back view of the roll holder shown in FIGURE 1, with the end bars generally perpendicular to the back bar;

FIGURE 3 is a back view of a portion of a modified form of roll holder embodying the invention with the end bar in folded relationship;

FIGURE 4 is a sectional view taken on line 4—4 of FIGURE 2 and looking in the direction of the arrows;

FIGURE 5 is a sectional view taken on the line 5—5 of FIGURE 3 with the end bar erected;

FIGURE 6 is a plan view in section of a small removed portion of another modified embodiment of the applicant's invention drawn to a larger scale than the other figures of the drawings; and

FIGURE 7 is a plan view in partial section of the modified embodiment of the holder shown in removed portion in FIGURE 6, with one end bar erected and the other end bar in folded relation.

One embodiment of the rolled article holder has a

2

longitudinally arcuate back bar 10, shown in FIGURES 4, 5 and 7, which may be formed of plastic by injection molding or the like. Transverse slots 11 and 12, shown in FIGURES 1 and 2, are formed in each of the longitudinal extremities of the back bar 10. Apertures 13 and 14, formed in a central portion 15 of the back bar 10 receive fastening means, such as screws (not shown) for attaching the back bar to a wall or the like. Recessed shoulders 16 and 17 are formed in the periphery of the longitudinal extremities of the back bar 10.

Identical hollow end bars or arms 18 and 19, which may both be formed of plastic by means of injection molding from the same mold, have means for attaching rolled paper towels and the like, such as the truncated hollow cylinders 20 and 21 on the ends of the opposing, inwardly disposed surfaces of the end bars 18 and 19. Projecting tongue means 22 and 23, formed on the end bars 18 and 19 on the edge opposite from the hollow cylinders 20 and 21 each have inwardly disposed laterally projecting elements 24 and 25, respectively. Detents 28 and 29 are formed on the transverse extremities of the laterally projecting elements 24 and 25 with a slope which progressively decreases the size of the detents as the edges of the laterally projecting elements 24 and 25 are approached. Projecting skirts or flanges 26 and 27 are formed on the outwardly disposed sides of the end bars 18 and 19 adjacent the tongue means 22 and 23 respectively.

The arms 18 and 19 are attached to the back bar 10 by pressing the laterally projecting elements 24 and 25 of the tongue means 22 and 23, downwardly and through the respective slots 11 and 12. The detents 28 and 29 on the transverse extremities of the laterally projecting elements 24 and 25 extend the tongue means in one dimension beyond the corresponding dimension of the respective transverse slot, while the wedge shape of the detents 28 and 29 facilitates snapping the tongue means through the slots. Thus the detents 28 and 29 function much like barbed fish-hooks, easily penetrating the slots 11 and 12, but blocking removal therefrom.

The tongue and detent is inserted for permanent, hinged retention in the back bar slots quickly, without the use of tools or machinery, permitting the end bars to rock freely from a position folded against the back bar to an unfolded, erected position without risk of detachment from the back bar. The tongue means 22 and 23 are slidably received within the slots 11 and 12 to hingedly cooperate with the end bars 18 and 19 thus facilitating the rocking motion.

The skirts or flanges 26 and 27, projecting from the outwardly disposed sides of the end bars 18 and 19 adjacent the tongue means 22 and 23, seat in the recessed shoulders 16 and 17, formed in the back bar 10, when the end bars are rocked to the erect position as illustrated in FIGURE 4. Thus the interrelationship between the flanges 26 and 27 and the shoulders 16 and 17 braces the erected end bars in a position generally perpendicular to the respective end portions of the back bar 10. The generally arcuate longitudinal shape of the back bar 10, illustrated in FIGURE 4, causes the end portions of the back bar to depend away from the surface to which the holder is attached. Consequently, the erected end bars 18 and 19 extend forwardly forming an acute angle with each other and with the central portion 15 of the back bar 10. The end bars 18 and 19 are thus sprung to resiliently engage a roll inserted between them for secure retention during use.

In another embodiment of the present invention, a rear view of which is shown in FIGURE 3 with the end bar 19 folded, and a section view of which is shown in FIGURE 5 with the end bar erect, has the projecting tongue means 23 and the laterally projecting element 25

slidably received in the transverse slot 11. A tapered 5
detent 30, centrally disposed on the side of the laterally
projecting element 25 adjacent the back bar 10, and a
recess 31, formed in the periphery of the slot 11 to ac-
commodate the detent 30 when the end bar 19 is rocked
into the position folded against the back bar 10, shown
in FIGURE 3, facilitates attaching the end bar to the
back bar and the sliding retention of the end bar on the
back bar 10 in the manner hereinbefore described.

A third embodiment of the applicant's invention, shown
in FIGURES 6 and 7 provides for the tongue means 23,
formed on the end bar 19, to be slidably received in the
transverse slot 11 on the back bar 10. The detent 30,
which in this embodiment of the invention may extend
along the entire transverse length of the laterally pro-
jecting tongue element 25, is of slightly greater width
than the slot 11. The detent 30 may, for example, be
only two-thousandths of an inch (.002") greater in width
than the slot 12 to permit the tongue on the end bar to
be snapped through the slot, permanently securing the
end bar in slidable relation with the back bar 10 in the
housing recess 31 in the manner hereinbefore described.
The flange 27 is seated on the shoulder 17 formed on
the longitudinal extremity of the back bar when the end
bar 19 is extended, while a protruding boss 32, formed by
the recessed shoulder 17 fits in snug engagement within
a recessed portion 33 of the end bar 18.

As is apparent from the foregoing, the present invention
provides a holder for supporting rolled articles, such
as paper towels and the like which is sturdy, inexpensive
and easily assembled.

While representative embodiments of the present in-
vention have been shown and described for purposes of
illustration, various changes and modifications can be
made therein as pointed out above without departing from
the principles of this invention. Therefore, all such
changes and modifications are included within the in-
tended scope of the invention as defined by the follow-
ing claims.

I claim:

1. A holder, comprising a back bar, lateral end por-
tions on the back bar, the lateral end portions each hav-
ing at least one transverse slot therein, a plurality of end
bars, at least one downwardly and laterally projecting
tongue means on each of the end bars cooperating with
the respective transverse slot and slidably received therein
for rocking movement of the end bar from an erect
to a folded position, detent means protruding from the
laterally projecting portion of each of the tongue means
and spaced from the respective end bar to render one di-
mension of the tongue means greater than the correspond-
ing dimension of the cooperating slot to lock the tongue
means within the slot, a recessed shoulder formed in the
periphery of each of the lateral end portions of the back
bar, and flange means on the end bars adjacent the tongue
means cooperatively seated on the recessed shoulder when
the end bars are rocked to an erect position.

2. A holder, comprising a back bar, lateral end por-
tions on the back bar, the lateral end portions each having
at least one transverse slot therein, a plurality of end
bars, at least one downwardly and laterally projecting
tongue means on each of the end bars slidably movable
within the transverse slot for rocking connection of the
end bars with the back bar, a transverse edge terminating
the laterally projecting portion of the tongue means of

each of said end bars and spaced from the respective end
bar, detent means formed medially on the transverse edge
rendering one dimension of the tongue means greater than
the corresponding dimension of the cooperating slot to
lock the slidable tongue means within the slot, recess
means formed in the periphery of each of said transverse
slots for receiving the detent means when the respective
end bar is rocked into folded relation to generally overlie
the back bar, a shoulder formed in the periphery of each
of the lateral end portions of the back bar, and flange
means on the end bars adjacent the tongue means co-
operatively seated in the recessed shoulder when the end
bars are rocked to an erect position.

3. A holder, comprising a back bar, lateral end por-
tions on the back bar each having at least one transverse
slot therein, a plurality of end bars, at least one down-
wardly and laterally projecting tongue means on each
of the end bars cooperatively received within one of the
transverse slots and slidably movable therein for rocking
movement of said end bar from an erect position to a
folded position relative to the back bar, a transverse edge
terminating the laterally projecting portion of each of the
tongue means and spaced from the respective end bar,
detent means formed on at least one of the transverse
extremities of said edge and rendering at least one di-
mension of the tongue means greater than the correspond-
ing slot dimension to lock the slidable tongue means with-
in the slot, recessed shoulders formed in the periphery
of the lateral end portions of the back bar, and flange
means on the end bars adjacent the tongue means co-
operatively seated in the recessed shoulder when the end
bars are rocked to an erect position.

4. A holder, comprising a back bar, lateral end por-
tions on the back bar each having at least one transverse
slot therein, a plurality of end bars, at least one down-
wardly and laterally projecting tongue means on each
of the end bars cooperatively received within one of the
transverse slots and slidably movable therein for rocking
movement of said end bar from an erect position to a
folded position relative to the back bar, a transverse edge
terminating the laterally projecting portion of each of the
tongue means and spaced from the respective end bar,
detent means formed on the transverse edge extending
substantially the entire length of said edge to render
at least one dimension of the tongue means greater than
the corresponding slot dimension to lock the slidable
tongue means within the slot, a recess formed in the back
bar adjacent to each of said slots to accommodate the
respective laterally projecting portion of said tongue means
and said detent means in nested relation therewithin
when each of said end bars are rocked into the erect
position, a boss on each of said laterally end portions
spaced outwardly from the respective slot, and flange
means on each of said end bars adjacent to the tongue
means for rockably engaging over the respective bosses
when said end bar is rocked into an erect position.
